OPENER FOR HAIRPINS

Peter E. Formica, Bridgeport, Conn.

Application November 20, 1947, Serial No. 787,062

5 Claims. (Cl. 132—1)

1

This invention relates to a device for opening folded hairpins, particularly hairpins of the so-called "bobby" type, and has for an object to provide a simple and effective means for opening these pins preparatory to applying them to the hair with a simple and easily performed operation.

Another object is to provide such a device which will occupy little space and may be readily carried and set up for use.

With the foregoing and other objects in view I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a partial end view and partial section of one form of the device showing the method of use;

Fig. 2 is a side view looking from the right of Fig. 1;

Fig. 3 is a view similar to Fig. 1 showing a somewhat modified construction, and

Fig. 4 is a top plan view of the device of Fig. 3.

In their normal condition, folded hairpins, particularly those of the so-called "bobby" type, comprise two side members or legs folded to lie closely adjacent and side by side, one leg being somewhat longer than the other, and in applying these to the hair it is normally necessary to separate these leg portions to open up the pins. Various methods are employed for this opening operation, a common method being to use the teeth, with resultant injury to the teeth by notching or cracking of the enamel, and other devices have been devised, some comprising a device to be held between the teeth and others involving more or less complicated devices to be used on a dressing-table or other support.

The present device is designed to overcome the objections of these prior devices and to more efficiently and easily perform the operation of opening such pins and also to devise a device which may be readily carried and set up or anchored in place of use. Referring first to Figs. 1 and 2, the device comprises an upright block 10 which may be formed of any suitable material, but preferably is made of some molded plastic material and is of general wedge shape, as shown in Fig. 1, with its narrowest edge 11 at the top, and the opposite side walls 12 tapered downwardly and outwardly in opposite directions

2

from this edge, and preferably these surfaces are curved somewhat, as shown, to provide convex outer surfaces. In its side walls, and also preferably across the end walls, the device is provided with horizontal grooves 13 and 14 providing an abrupt upper shoulder 15 which may be used to grip and hold the end 16 of the longer leg 17 of a folded hairpin 18 of the "bobby" type of pin, as shown at the left of Fig. 1, so that by 10 forcing upwardly on the other leg 19 it may be opened as indicated. The general wedge shape or tapered form of the device can also be used as a wedge to open these pins, as indicated by the pin 18a and its dotted line position. In this 15 use of the device, the open end of the pin is placed with the free ends of the legs straddling the upper edge 11, as shown in full lines Fig. 1, and then forced downwardly to the dotted line position, during which action the tapered shape of the block acts as a wedge to separate the legs or open the pin so that it may be held in this position by fingers of the user for application to the hair.

Some suitable means is provided to support 25 and anchor the device and hold it stationary when in use. That shown in Figs. 1 and 2 comprises a rubber vacuum cup 20 secured to the lower side of the block 10 by any suitable means, such, for example, as forming the block 10 with a flanged extension 21 and molding it into the upper part of the cup 20. This forms a very effective means for supporting the device on and anchoring it to some supporting medium, such as the top 22 of a dressing table or a mirror or 30 any other suitable supporting means. In the form of Figs. 3 and 4, instead of using the flexible rubber vacuum cup 20, the block is mounted on a cupped sheet metal or plastic member 23 having a flange 24 by means of which it 35 may be secured to the supporting means 22 by any suitable fastening means, such as the screws 25. The block 10 may be mounted and secured to the supporting means by any suitable means, such, for example, as a threaded stud 26 secured 40 in the lower end of the block passing through the member 23 and secured by any suitable nut 27.

It will be seen from the above that the device 45 is a very simple one and may be easily carried in a handbag; also that it may be readily secured and anchored in use, and is very rapid in operation in opening this type of hairpin, in that it requires merely either a downward motion from the top of the block with the pin 50 in the upright position, as shown at 18a, Fig. 1,

or the pin when held in the thumb and fingers may be passed upwardly over the outer surface to bring the free end 16 of the longer leg into one of the grooves or under one of the shoulders 15 where it is held while the other leg is forced upwardly to open the pin, as indicated at 18 in Fig. 1. This is a very simple operation and may be done very rapidly. The curved or convex surface 12 facilitates both of these different operations, the curvature preventing the ends of the pins becoming seated and then stopped by the groove in forcing the pin downwardly from the top in the wedging action, and the curvature readily guiding the end of the pin into the groove or to a position to engage the shoulder at the top of the groove, this curvature causing in effect a slight overhang of the shoulder so that it is readily engaged by the end of the pin. In either mounting for the block it is rigidly held and anchored to readily overcome any force which may be necessary to be applied to the device in the pin opening operation, and therefore it is not necessary to use both hands in opening the pins.

Having thus set forth the nature of my invention, I claim:

1. In a device of the character described for opening hairpins, an upright block having inclined side walls extending downwardly and outwardly from an upper longitudinal edge, said side walls being provided with a longitudinal groove including an abrupt shoulder at the top of the groove adapted to engage and hold the end of the longer leg of a "bobby" type of pin to open it by upward pressure on the pin, and a support for the block.

2. A device of the character described for opening hairpins, comprising an upright block including a longitudinal top edge and downwardly and outwardly convexly curved side walls on opposite sides of said edge forming a substantially wedge shaped block, each side wall being provided with a longitudinal groove including a shoulder at the upper edge of the groove adapted to engage and hold the end of the longer leg of a "bobby" type of pin to open it by upward pressure on the pin, and a support for the block.

3. A device of the character described for opening hairpins, comprising an upright block provided with side walls inclined downwardly and outwardly from an upper longitudinal edge, said side walls being provided with longitudinal downwardly facing shoulders to engage and hold the end of the longer leg of a "bobby" type of pin while upward pressure is applied to the other leg to open the pin, and a support for holding the block.

4. A device of the character described for opening hairpins, comprising an upright block including a longitudinal top edge and downwardly and outwardly inclined convexly curved side walls on the opposite sides of said edge forming a substantially wedge shaped block, each side wall being provided with a longitudinal shoulder adapted to engage and hold the end of the longer leg of a "bobby" type hairpin while force is applied to the other leg and shift it away from the first leg to open the pin, and a support for holding the block.

5. A device of the character described for opening hairpins, comprising a substantially wedge shaped block including side walls and a longitudinal edge at the junction of said walls, one of said walls being an inclined side wall extending way from said edge, said side wall being provided with a longitudinal shoulder arranged to engage and hold the end of the longer leg of a "bobby" type hairpin while force is applied to the other leg to shift it away from the first leg to open the pin, and a support for holding the block.
